UNITED STATES PATENT OFFICE.

JOSEPH CHARLES OSTERN, OF SAN FRANCISCO, CALIFORNIA.

TAILOR'S AND LAUNDRY IRONING-TABLE.

1,074,328.

Specification of Letters Patent. Patented Sept. 30, 1913.

Application filed August 14, 1912. Serial No. 715,025.

To all whom it may concern:

Be it known that I, JOSEPH CHARLES OSTERN, a citizen of the United States, residing in the city and county of San Francisco and State of California, have invented new and useful Improvements in Tailors' and Laundry Ironing-Tables, of which the following is a specification.

This invention relates to ironing tables.

10 The object of the present invention is to provide an improved ironing table, particularly designed for laundry and tailors' use; the device being constructed substantially, and includes peculiar stiffening and bracing elements tending to obtain the desired 15 rigidity and strength to stand the strains to which the apparatus is subjected.

A further object of the invention is to design and provide an ironing-board involving details of construction designed for the purpose of enabling the better ironing and pressing of wearing apparel, or other articles, and to support the same while being 20 pressed to prevent disfiguring, wrinkling 25 and creasing of the article.

The invention consists of an ironing-board, and details of construction which will be more fully explained by reference to the accompanying drawings, in which—

30 Figure 1 is a perspective view partly broken away. Fig. 2 is a plan view of the adjustable pedestal.

In laundry and tailor establishments where great varieties of articles are to be 35 ironed, cleaned, or pressed, it is desirable to have an apparatus capable of various adjustments, whereby the ready manipulation of the articles to be pressed may be had; the structure being capable of bracing to stand

40 the strains and designed to most effectually accomplish the desired condition. In accomplishing these purposes I employ a suitably shaped and proportioned table, such as 2, upon which may be secured, at a suitable 45 height above the table 2, a proportionately shaped and proportioned ironing-board 3 connected by a transverse bearing 4, which is secured to the table 2. The ironing-board 3 projects well to one side of the bearing 4 above the table 2, and is stiffened somewhat 50 by a diagonal brace 5 which is abutted against the bearing 4 and the contiguous portion of the table 2; the outer end of the brace 5 being secured to the lower surface of 55 the ironing-board 3, adjacent its central portion. The diagonal brace beneath the iron-

ing board 3 permits the adjustment beneath the board 3 of a portion of a garment, or other article, while another portion is being rested upon and pressed on the upper surface of the board 3. The brace 5 is designed, not only for the purpose of allowing clearance substantially the full length beneath the board 3, but also to support the board against too great downward flexure; but when certain articles, as coats of heavy material are being pressed, then the great pressure applied by the iron to press the material would, unless resisted by additional means to the brace 5, bend the board 3 too much, so one of the features of my invention is to provide a drop leg 6, which is hingedly or otherwise connected, as at 7, to the lower surface of the board 3, and which may be dropped to the position indicated in Fig. 1, 75 when it is desired to further support the board 3 in addition to the brace 5. When the drop leg 6 is not in use it is swung upwardly beneath the board 3 and engaged by a snap hook 8 thereon, thus again leaving 80 clearance space beneath the board 3 for the insertion of portions of articles being pressed.

In different establishments where the apparatus may be used, the table 2 may be supported directly upon a shelf, bench, table, or other structure; or if desired, the table may be supported upon an adjustable pedestal, comprising foldable legs 9 which extend upwardly above their pivotal transverse 90 brace 10, the outer upper ends of the legs 9 being designed to over-lap the long edges of the table 2, which I have shown as bound by a wearing and reinforcing bar 11, preferably of metal.

95 The elevation of the table 2 may be adjusted by means of a thumb nut 15 and screw 12, or other appropriate means, which extends between transverse rocking braces 13 which are pivotally connected to the upper ends of the legs 9, and upon which the table 2 is deposited. The support braces 13 are turnably mounted on their pivots 14 of the legs 9, so that the upper flat surfaces of the braces 13 can be maintained in a common 100 horizontal plane when the screw 12 is adjusted to raise or lower the upper ends of the legs 9; the braces 13 being drawn toward or allowed to spread from each other on the screw 12, by the turning of the wing nut 110 15 on the screw 12, which determines the distance between the parallel braces 13.

Another important feature of my invention is the provision of an adjustable flexible device in combination with the apparatus, which is adapted to support such over-hanging portion of a garment which is being pressed upon the board 3. For instance, when an evening or other full length dress is being manipulated, while the skirt of the dress is being pressed upon the board 3, the 10 waist and neck would, if not appropriately supported, dangle loosely over the outer end of the board 3, and thus become wrinkled and creased after being pressed, and to prevent this I provide a supporting device consisting of a standard 16, having a clamp or other appropriate means 17 for attachment upon a slide bar 18, which is adjustable in a suitable bearing 19 at one side of the table 2. From the upper, over-hanging end of the 20 upright 16 depends a flexible cord, chain, or some equivalent 19', to which may be hooked, laced, or properly connected that portion of the garment which projects beyond the outer end of the ironing-board 3. The 25 purpose of the flexible suspending cord or chain 19' is to permit, in addition to supporting the over-hanging portion of the garment, the gradual turning of the garment while it is being pressed on the board 3. The 30 turning of the garment twists the cord 19' automatically.

Preferably the table 2 is of somewhat greater length than the board 3, thus affording an area 20 upon which may be rested an 35 iron or irons, thus leaving the upper surface of the ironing-board 3 entirely clear from obstruction. The rigidity of the main ironing-board may be increased by connecting the same to the diagonal brace by means 40 of a through-bolt 24, and an oblique brace 25.

Having thus described my invention, what I claim and desire to secure by Letters Patent, is—

1. An ironing table having a pressure 45 board about which pieces being ironed may

be turned and a suspension device attached to the table and having a twistable part overhanging the longitudinally projected plane of the board for turnably suspending portions of pieces overhanging the end of 50 the board while being pressed and turned on the board.

2. A tailor's and laundry ironing table comprising an elevated table having an ironing board attached at one end thereon and 55 spaced above the table for permitting the interposition of portions of pieces to be ironed, and a flexible garment supporter, longitudinally adjustable along and overhanging the plane of the table for holding 60 attached portions of articles in the process of ironing on the board.

3. A tailor's and laundry ironing board comprising a table member, an ironing board spaced above and attached to the 65 table, and an upwardly extending standard longitudinally adjustable along the table and having a flexible garment supporter overhanging the plane of the board and to which a garment being ironed may be attached and supported about in the plane of the ironing board, whereby that part of garment is prevented from engagement with adjacent surfaces and from creasing.

4. An ironing table comprising a table 75 part and an ironing board above and supported thereon, a slide longitudinally adjustable on the table, a standard attached to said slide having a flexible connection whereby pieces being pressed are supported about 80 in the plane of the board when secured to said connection.

In testimony whereof I have hereunto set my hand in the presence of two subscribing witnesses.

JOSEPH CHARLES OSTERN.
